DIALYZER

John Felix Marchand, New York, N. Y.

Application August 24, 1949, Serial No. 112,037

5 Claims. (Cl. 210—8.5)

1

This invention relates to a dialyzer and more particularly to apparatus of both the filter-press and tubular type for clarifying liquid and gas solutions to eliminate or reduce or interchange the content of solutes from such solutions.

The efficiency of presently used types of dialyzers has been limited because there has been no fully satisfactory method for holding the membranes, whether made of parchment, cellulose, or other material, in precise alignment suitable for optimum effectiveness of operation. Various types of reinforcing units have been employed either to support the membranes, or to provide for a high surface acting flow of the solution being dialyzed.

The effectiveness of such apparatus has been limited by a lack of adequate elasticity and flexibility in the membrane supporting devices. Although rubber has been used for gaskets and grids, it was employed only because it was soft enough to decrease the risk of tearing the membranes during their use in the dialysis process. As a result, such equipment had to be constructed with clearances adequate to allow for stretching and billowing of the membranes during their use, since all dialyzing membranes stretch and billow when wet. Dialyzing equipment heretofore used for large-scale continuous work has therefore been large and cumbersome.

With the above disadvantages in view, it is an object of the present invention to provide a dialyzer of compact and efficient construction adapted to overcome the objectionable features of presently used types of apparatus. This object is achieved by the use of a flexible member which holds the membranes tight and in precise alignment as they swell and stretch during their use. This feature permits construction of both tubular and filter-press types of dialyzers to much closer dimensions, incorporating a micro-film feature at the membrane interfaces, reducing dead space and providing a steep concentration gradient across said interfaces and favoring a relatively rapid attainment of equilibrium between the solutes of the solutions on the two sides of the membrane. A wide variety of liquid or gaseous solutions or mixtures may be dialyzed against one another across a semi-permeable membrane. The result is an interchange of one or more solutes until an equilibrium is attained of which the well-known Donnan equilibrium may be taken as an example. Without intending to exclude any of such theoretically possible combinations, I shall arbitrarily refer, for the sake of brevity and clarity, to two solutions, termed

10 (1) the dialyzable solution, and (2) the wash-water. Any gaseous or liquid solution or mixture may be substituted for either. It should also be understood that for the dialysis of aqueous systems the cellulose derivatives of animal membranes are suitable, while for the dialysis of alcohols or other organic solvents, other membranes, notably rubber, or Vinylite, may be employed.

15 Another object of the present invention is to provide a compact, flexible, flaccid, easily disposable and disconnectable dialyzer unit which can be readily assembled and utilized.

In tubular dialyzers certain features of design have limited the efficiency and general use of such apparatus for industrial or biochemical purposes. One of these difficulties has been the lack of a satisfactory method of supporting the membranes in precise alignment for optimum efficiency. Another has been the difficulty arising from the necessity of replacing a long tube when a leak occurs. Such dialyzing tubes are usually suspended in a bath or mounted in a rigid outer duct.

20 25 In the present invention, these difficulties are overcome by the use of flexible members as more specifically described herein, and by the provision of a dialyzing tube which is subdivided into a series of easily replaceable or interchangeable units of novel design. In order to make these smaller units easily interchangeable, they are made flexible and equipped with fluid connections, the ends of which may be readily connected or disconnected without necessitating a shutdown or dismantling of the apparatus as a whole. Standard-taper connections of the type used with hypodermic syringes and needles are suitable for this purpose, but any other easy type of connection may be substituted. By means of these relatively inexpensive, multiple, interchangeable, disposable, standardized units, the capacity of the dialysis assembly as a whole may be varied according to the needs of the moment.

25 30 35 40 45 50 55 For use with ordinary tubular dialyzing membranes, a unique feature of this novel type of unit is the provision of flexible supporting grids which not only hold the membranes in proper alignment for optimum effectiveness, but also guide the flow of solutions in an expeditious and favorable manner. That is, the grids serve as fluid spreading members. Said grids also are flexible and springy enough to expand as the tube stretches or expands, and to bend and flex with the tubes as they bend or flex during installation, or removal, or use. The edges of these

grids may be rounded, smooth, or folded under to avoid cutting the membranes they support. By correcting the tendency of the dialyzing membranes to billow during use, these flexible spring-grids permit efficient operation to continue independently of variations in the hydrostatic pressure on the two sides of the dialyzing membranes. The flexible feature permits easy interchange or screwing together without risk of breakage.

Around the dialyzer tubes themselves are mounted additional flexible grids. These outermost flexible spring-grids conduct in a favorable manner the solution against which the contents of the inner dialyzing tube is being dialyzed. At the same time, these outer grids support a flexible outer retaining tube which is impermeable and relatively tough and bends with the unit as a whole; all parts being preferably transparent, easily sterilized, boilable, and chemically inert with respect to the solutions or gases to be treated.

Other objects and features of my invention will become apparent from the following detailed description taken in connection with the accompanying drawings, in which:

Fig. 1 is a sectional view of an elementary unit forming part of my invention;

Fig. 2 is a longitudinal, sectional view taken on line 2—2 of Fig. 1;

Fig. 3 is a somewhat enlarged detailed view taken on line 3—3 of Fig. 1;

Fig. 4 is a plan view of an embodiment of my invention including a unit similar to the type shown in Fig. 1;

Fig. 5 is a fragmental, enlarged, sectional, detailed view of the embodiment shown in Fig. 4;

Fig. 6 is a longitudinal, fragmental view of another embodiment of my invention containing a unit such as that shown in Fig. 1;

Fig. 7 is a front, sectional, partly broken away, elevational view of another embodiment of the invention;

Fig. 8 is a sectional view taken on line 8—8 of Fig. 7 showing the details of arrangement of parts;

Fig. 9 is a sectional detail view taken on line 9—9 of Fig. 8 showing the relation of the cells containing dialyzable fluids and wash fluids;

Fig. 10 is a sectional view of another modification of the embodiment shown in Fig. 1;

Fig. 11 is a section taken on the line 11—11 of Fig. 10;

Fig. 12 is a sectional view of a modification of the embodiment shown in Fig. 5; and

Fig. 13 is a sectional view taken on line 13—13 of Fig. 12.

Referring now to the drawings in which like numerals refer to like parts throughout, it will be noted that by my invention there is provided a fluid dispersing or grid member 10 made of any suitable, more or less resilient material such as rubber, metal, glass, or one of the synthetic plastics or resins which is enclosed in a flexible tubular expandable member or sac 11 of suitable permeable material, such as regenerated cellulose, cellulose nitrate, cellulose acetate, parchment or animal membrane. Said grid member 10, as shown more clearly in Fig. 1, is obliquely corrugated and provided at its marginal edges 12 and 13, respectively, with notches or perforations 14 so as to effect a spiral, swishing or turbulent flow of a solution of dialyzable material in its passage along the faces of the member 10 from one end to the other thereof. This action so produced will effectively increase the surface activity of the

solution and thereby increase diffusion of solutes through the wall of member or sac 11.

The sac member 11, as shown in the drawings, is co-extensive with the grid member 10 and is adapted snugly to enclose or retain the same. Said sac member 11 is preferably cylindrical and is flattened by retaining the member 13. Said sac is normally flaccid and open at each end for accommodating at each of said ends a tubular member 15 which is provided with an annular flange 16 at its terminal portion and another annular flange 17 at any desired distance from the terminal portion of said tubular member 15 so as to accommodate a rigid or flexible fastening member or collar 18 of rubber or cement or any suitable material, thus holding the terminal portion of the sac 11 against the outside of the tubular member 15 in the area between said flanges 16 and 17. The details of such connection are shown more clearly in Fig. 2. It will be noted that the embodiment shown in Fig. 1 is a unit and can be utilized alone or in connection with any of the subsequent modifications shown and described hereinafter. Any convenient number of such units may be connected in series or in parallel.

Instead of having a member provided with oblique corrugations as shown in Fig. 1, I may provide a grid fluid-dispersing member 19 having corrugations 20 disposed at right angles to the longitudinal axis of said member 19 such as shown in Figs. 4, 5, and 6. In conjunction with this right angle inner grid, obliquely corrugated outer grids of the same or larger size may be employed. Each grid is provided with openings or notches 21 alternately disposed on each marginal edge of the grid as shown.

Said unit consisting of the grid 19, a flaccid, expandible permeable sac 22 similar to sac 11, tube 15, and collar 18 is enclosed in an outer tubular flexible member or sac 23 containing a pair of grid members 24 and 25 disposed in said outer sac 23 and pressing against the intermediate inner sac 22. Said outer sac may consist of any suitable type of sufficiently impermeable material such as polyethylene, polyvinylite, rubber, glass, cellulose nitrate, cellulose acetate, or nylon. The outer sac 23, as shown, is fixed at its terminal ends respectively to stopper members 26 and 27 respectively. Said stopper members may be made of rubber or of any other suitable material and are each provided with openings 28 and 29, respectively, for accommodating tubular members 30 and 31, respectively, which are in connection with Y-members 32 and 33, respectively. Each of said stoppers 26 and 27 is provided with an opening 34 for accommodating tubular member 15. It will also be noted that the outer sac 23 of the modification shown in Figs. 4 and 5 has its ends snugly fitted to the stoppers 26 and 27 in any suitable manner.

The inner unit, as shown, is provided for the passage therethrough of any suitable dialyzable fluid, solution or gas mixture, while the outer sac 23 with its respective grid members 24 and 25 is adapted to permit the passage therethrough of water or a second solution or gaseous mixture forced through the sac in a direction counter-current to the first. Both the first dialyzable fluid or gas and the second solution (against which said fluid is dialyzed) pass through the device counter-current to each other, and, as they pass over the respective grids, do so in a swirling manner.

In the embodiment shown in Fig. 6, there is provided an inner unit of a construction substan-

tially the same as that shown in Fig. 1, with the opposed terminal tubular members 45, each extending through stoppers 35 and 36, respectively, mounted onto the ends of a water conducting tube 37 provided with an inlet 38 and outlet 39 for permitting the flow of fluid into and out of said tube 37.

In Figs. 7-9, inclusive, there is shown another embodiment of my invention known as the filter-press type of dialyzer provided with end channels whereby the dialyzable fluid enters at one side and after diffusion comes out from the other side, and the wash fluid enters at a side opposite the entering dialyzable fluid. Said device, as shown, is provided with a plurality of end frame members 48 and 49, and side members 42 and 43. Said end members are held in position by means of rods 44 extending through the frame members at spaced intervals thereof to retain the shape of the said frame members. Each of said rods is threaded at one end for accommodating winged nuts 45. Adapted to be retained in the framework formed by members 40 and 41, and side members 42 and 43, is a plurality of superimposed, preferably transparent plates 45, each of the same construction as shown in Figs. 7 and 8. Each of said plates is provided with a number of cut-outs or spaces 46 of relatively large size extending across the face of the plate, said spaces being parallel to each other and lying in the same plane. Each of said plates, furthermore, are also provided on their face with terminal recesses or grooves 47 and 48, respectively, in connection with lateral recesses or conduits 49 and 50, respectively, which are in connection with an inlet conduit or groove 51 in member 40 and an outlet conduit or groove 52 in member 41, respectively. Said inlet 51 has an opening 53 for inlet tube 54. It will be noted from the views shown in Figs. 7 and 8 that, when said plates 45 are superimposed, passageways are formed for the flow therethrough of dialyzable material. Said plate frames 45 are held in rigid superimposed position by means of screw members 55 fitted at spaced intervals into the side members 42 and 43, respectively.

In this type of construction, it will be noted that each of said plates is disposed face to face and provided with membranes or diaphragms 56 and 57 between which is disposed a grid baffle plate or member 58 in each of the openings 46, so as to hold said membranes taut and smooth as they stretch to form a cylindrical bulge. Said members are provided with notches or openings 59 to permit swirling or turbulent action or movement of the dialyzable fluid passing through the passages 60 between the diaphragms or membranes 56 and 57 and containing the grids 58 as shown more clearly in Fig. 7. The use of said flexible baffle plates 58 holds the membranes in close alignment as they stretch and permits frame construction to closer tolerances with resulting increased operating efficiency and, at the same time, provides a spiral flow accelerating the rate of passage of the dialyzable solution over the membranes and speeds diffusion by shortening the diffusion gradient and minimizing surface formation at the membrane interface. The plate members may be clamped together for either series or parallel current flow through the 70 alternating frames in the usual manner. Furthermore, the type of grid members, as indicated hereinabove and shown in the drawings, may be replaced by spring grid members of suitable flexible plastic or metallic material such as

shown in Figs. 10-13, inclusive, with apertures at or near alternating margins in such a way as to cause a spiral flow about the grid and against the membranes. As the membranes become wet and stretch or billow, the grid by its spring action expands so as to hold the membranes in a taut and flat condition. This grid further increases the efficiency of the apparatus by permitting the construction of relatively thick wash-water cells which may encroach the frame limits of the cells of solution to be dialyzed.

The wash-water, according to the sectional view in Fig. 7, is shown as entering the inlet 54 and going out through outlet conduit 52 and outlet 61, while the fluid to be dialyzed enters through inlet 62 and leaves through outlet 63. It will be noted from Figs. 8 and 9 that the plates 45 are so arranged that the pairs of plates are disposed with their recesses 47 and 48 and 49 in face to face relationship so as to form passages for the flow of the solution in one direction and the flow of the wash fluid in another direction. In Fig. 8 the dialysis cells 55 and 57 contain the grid members 58 so that, as the solution enters 25 into the passageway between the diaphragms at one end, the solution passes over the members and passes out through outlet 65.

In the modification shown in Figs. 10-13, inclusive, it will be noted that I have provided, instead of a grid member, a flexible resilient, spring-like member 65, which when inserted into the permeable sac member 66 has a tendency to expand and keep said permeable member in a taut, relatively flat position as shown more particularly in Fig. 11. This unit, as is shown in Fig. 10, is adapted to permit the flow of a dialyzable fluid through inlet 67 of stopper member 68 into the permeable member 66 whereupon the dialyzable fluid by means of member 65 will be brought into contact with the permeable member whereby diffusion results and the fluid will continually pass through said sac and out through exit tube 69 in stopper 70.

In Fig. 12, there is shown a modification in which the inner membrane 71 is made of permeable material and accommodates a spring-like member 72 adapted to stretch said permeable member as shown. Said permeable member is provided with an inlet 73 and outlet 74 at its ends 75 and 76, respectively, so as to permit the passage through the permeable membrane of any type of fluid which is to be dialyzed. This inner portion is enclosed in an outer container or sac 77 made of impermeable material which is provided with one or more flexible tension members 78 which may be placed above each other as shown in Fig. 13 and adapted to stretch impermeable member 77. It is to be noted that said impermeable member is connected at each of its ends 78' and 79, respectively, to stopper members 80 and 81 of any suitable type of material. One of said stoppers 80 is provided with one or more inlet conduits 82 and 83, while the other stopper member 81 is provided with one or more outlet conduits 84 and 85 whereby suitable types of washing fluid may be forced through said permeable sac in a suitable manner counter to the flow of the dialyzable fluid passing through the inner permeable member.

From the foregoing description taken in connection with the accompanying drawings, it will be noted that I have provided an invention permitting effective and rapid dialysis or diffusion of any type of fluids or gases whereby they can be readily purified or altered by a relatively con-

stant swirling or turbulent action. Such a device made according to my invention is compact, easy to make and operate, and can be made of any suitable material where the dialysis and passage of fluids can be readily observed. Furthermore, the parts in a device made according to my invention are easily sterilizable, easily replaceable, and inexpensive, so that the invention can be effectively used as an assembly of disposable units for biochemical, medical, industrial or other suitable purposes. I have found, furthermore, that the flow of wash fluid around the permeable member in the ratio of ten volumes to one of the dialyzable fluid passing through the permeable member produces the best 15 results for dialysis or diffusion.

Having described illustrative embodiments of the invention, it is pointed out that various changes and modifications therein may be made without departing from the invention as set forth in the following claims.

I claim:

1. A tubular, easily portable and disposable compact dialyzing device comprising a permeable normally flaccid readily expansible tubular sac 25 member, a flexible, easily bendable corrugated grid member contained by the tubular member, said corrugation forming spaced contacts with the interior of the tubular member, said grid member containing a series of alternately disposed marginal openings to set up a swishing motion of fluids passing through the tubular member, another tubular expandible impermeable sac member surrounding said first member, a pair of corrugated grid members one on either side of the inner tubular member adapted to flex with the tubular members, and inlet and outlet means for each of said tubular members, said device being easily flexible and disassembled.

2. Tubular dialysis apparatus for removing diffusible materials from a mixture or solution comprising a freely expansible and flexible sac unit defining an expansible passageway adapted to convey a dialyzable fluid therethrough, said unit including a permeable member enclosing fluid spreading expansible and contractible grid means having a series of alternately disposed marginal openings adapted to permit the dialyzable fluid to swirl through the passageway and help dispose of solutes contained therein, another freely expansible and flexible unit enclosing said first unit adapted to conduct a washing fluid therethrough to carry away solutes permeating the first named unit, inlet means in connection with the first unit for the passage of dialyzable fluid into said first unit, outlet means connected to said first unit for the resultant dialyzed fluid, and inlet and outlet means in connection with the unit containing the washing fluid, said sac unit being adapted to expand and contract in volume when fluids flow therethrough.

3. Tubular dialysis apparatus comprising a flexible, yieldable, uneven surfaced fluid spreading first member having successive alternate notches for agitating passing fluid in a series of continuous short diagonal directions, a membrane of flexible, expansible permeable material surrounding said first member adapted to conform with the general outline of the first member to define a passageway and permit the passage through the membrane of solutes in fluid

conducted through the passageway, inlet and outlet means in connection with said membrane, an outer member of impermeable material substantially enclosing and containing said membrane provided with a pair of opposed fluid spreading second members adapted to rest against the membrane and yield therewith when fluid passes through the passageway, and inlet and outlet means for said external member adapted to permit the flow therethrough of wash fluid to wash off the diffused material of the fluid passing through the passageway, said membrane being adapted to form a cylindrical bulge when fluids are passing through the passageway.

4. Tubular dialysis apparatus comprising a yieldable flexible fluid spreading member, an expansible permeable membrane defining a passageway and surrounding the member, said members adapted to permit the swirling passage of fluid conducted through the passageway, inlet and outlet means for said passageway, an external member of impermeable material enclosing and concentric with said membrane provided with a pair of opposed fluid spreading members adapted to rest against the membrane and yield therewith when fluid passes through the passageway, said opposed fluid spreading members having diagonally opposed recesses to effect swirling of fluid therethrough, and inlet and outlet means for said external member adapted to permit the flow between the membrane and the external member of wash fluid in a current counter to that of the fluid passing through the passageway.

5. Tubular dialysis apparatus comprising a yieldable, corrugated fluid spreading member, an expansible, flexible membrane defining a passageway enclosing the member adapted to permit the passage through the membrane of solutes in fluid conducted through the passageway, dialyzable fluid inlet and outlet means for said passageway, an external member of impermeable material containing said membrane provided with opposed corrugated diagonally opposed, marginally notched fluid spreading members adapted to rest against the membrane and yield therewith when fluid passes through the membrane and expands the same, and inlet and outlet means for said external member adapted to permit the flow therethrough of wash fluid in a current counter to that of the fluid passing through the membrane.
